UNITED STATES PATENT OFFICE.

CHARLES WILLIAM WETTER, OF ST. GALLEN, SWITZERLAND.

EMBROIDERING-MACHINE.

1,274,119.

Specification of Letters Patent. Patented July 30, 1918.

Application filed December 28, 1917. Serial No. 209,291.

To all whom it may concern:

Be it known that I, CHARLES WILLIAM WETTER, a citizen of the Republic of Switzerland, residing at St. Gallen, Switzerland, 5 have invented certain new and useful Improvements in Embroidering-Machines; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to a device for transferring colors to a piece of fabric framed in an embroidery machine.

The object of the invention is to provide a device of this kind provided with members 20 adapted to pierce through the fabric and a color-ribbon and to transfer the color from the ribbon to the fabric in which a carrier for color-ribbons is made of flat superposed casings adapted to act as guides for the ribbons and provided on the level of each color ribbon with holes arranged at a distance from one another corresponding to the repeat of the embroidery machine, the piercing members being adapted to be moved into 25 said holes and the ribbon-carrier being adapted to be adjusted in such a manner, that the casing containing the required color-ribbon can be brought on a level with the piercing members.

30 This invention will now be more particularly described with reference to the accompanying drawings, which illustrate several constructional examples of the invention.

In these drawings:

40 Figure 1 is a rear elevation of a part of an embroidery machine to which the novel device is applied.

Fig. 2 is a corresponding plan view.

45 Fig. 3 illustrates on an enlarged scale a front elevation of a detail;

Fig. 4 is a vertical cross-section on the line IV-IV of Fig. 3 and

Fig. 5 a cross-section on the line V-V of Fig. 3.

50 Fig. 6 shows the parts illustrated in Fig. 4 in another position.

Fig. 7 is a plan view of a further detail,

Fig. 8 being a corresponding vertical cross-section,

Fig. 9 illustrates diagrammatically the mechanism for actuating the punches.

Fig. 10 is a scheme illustrating the feed mechanism for the ribbons carrying the colors.

Fig. 11 is a cross-section through the color-carrier.

Fig. 12 is a figure corresponding to Fig. 6, illustrating a modification of a detail.

Fig. 13 is a cross-section on the line XIII-XIII of Fig. 12, and

Fig. 14 and 15 are a front elevation, partly in section, and a plan view respectively of a further modification of a detail.

Referring to the figures, 1 denotes a standard of an embroidery machine; 2 is the frame of the machine. 3 are shuttle tracks mounted on a bar 7. 4 denotes the needles, 5 the perforators and 6 the punches.

To the shuttle bar 7 are fixed U-shaped holders 8 distributed over the whole length of the machine. The holders 8 carry angle pieces 9 adapted to be moved transversely with regard to the fabric 10 stretched in the frame 2 of the machine. Each angle piece 9 carries a vertical slotted bar 11 arranged near the fabric 10 to be embroidered; on each bar 11 is mounted a flat bar 12 capable of being adjusted and having a fork-shaped top end. A pin 13 of the flat bar 12 extending through the slotted bar 11 is guided in a slot 14 of a lever 15. The latter is fixed to a shaft 16 carried by the holder 8. The shaft 16 carries also a lever 17.

The levers 17 are connected by means of a rod 18. To the end of the rod 18, facing with regard to the drawings the right hand side of the machine, i. e. the side on which is mounted the driving shaft 19, is fixed a tension member 20 connected at the other end to a hand lever 21. Lever 21 is pivotally mounted on a support 22 fixed to the standard 1 of the machine and it is adapted to engage into a toothed segment 23. A tension spring 24, which is connected at one end to the rod 18 and at the other end to a fixed part of the machine, exerts constantly a pull upon the member 20 and has the tendency to keep the flat bars 12 in their lowermost position. On each support 8 rests a slide member 24¹ provided with an inclined surface 25 (Fig. 5). 26 denotes a bolt fixed to the angle piece 9 adapted to engage that side of the slide member 24¹ which is pro-

vided with the inclined surface 25. A tension spring 27 connected at one end to the holder 8 and at the other end to the angle piece 9 presses the bolt 26 constantly against the slide member 24¹. The slide members 24¹ are connected by means of straps 28 and they are acted upon by tension springs 29. To the slide member 24¹ lying nearest to the driving shaft 19 is fixed a tension member 30 connected to a hand lever 31. The hand lever 31 is pivotally mounted in the same manner as lever 21, on the support 22 and it is adapted to engage into a toothed segment 32 of the support 22. The member 30 is constantly tensioned by the springs 29.

The fork-shaped ends of the flat bars 12 support a carrier A (Figs. 4, 3, 6) having the form of a flat bar and extending over the whole length of the machine. The carrier A is provided with three superposed flat casings, each of which acts as a guide for a color-ribbon 33 passing through it. The carrier A (Fig. 11) consists of two strips of sheet iron 34, 35. As shown in Fig. 11, the strip 34 is provided with cranked portions forming partition walls between the middle casing and the two outside casings extending from one side-wall of the middle casing to the side of the carrier lying opposite said side-wall and forming on this side the side-walls of the outside casings. This strip 34 is bent near the upper and lower ends of the carrier A at right angles, thus forming the outside end walls of the outside casings. As the strip 34 is bent a second time at right angles it forms also the other side-walls of the outside casings. The ends of this strip 34 are connected to the side-wall of the middle casing first referred to. The second side wall of the middle casing is formed by the strip of sheet iron 35 fixed to the side walls of the sheet iron strip 34 which lie on the same side of the carrier A. Each of the casings formed by the sheet-iron strips 34, 35 is provided with a plurality of holes 36, the distance between these holes corresponding to the repeat of the embroidery machine or distance between corresponding portions of successive patterns.

To each of the two outside supporting rods 37 for the shuttle bar 7 is fixed a support 38. To each support 38 is fixed a shaft 39 (Figs. 7 and 8) on which is loose a ratchet wheel 40. Pins provided on a three-part roller 41 carrying the color-ribbons and mounted on the shaft 39 are adapted to engage into said ratchet wheel 40. 42 denotes a spring adapted to exert a brake action upon the rotatable roller 41. Two pawls 43, 44 are also adapted to engage into the ratchet wheel 40, the pawl 43 being pivotally mounted on the support 38 and acting as a locking pawl. The pawl 44 is mounted on a lever 45 pivotally connected

to the support 38 and it is adapted to act as a feed pawl. Lever 45 is acted upon by a tension spring 46 and it is also connected to a lever 49 mounted on a shaft 48 by means of a tension member 47 passing around a guide roller or rollers 150 on the machine frame (Figs. 2 and 10). The pawls 43, 44 are adapted to be set in and out of operation. The ribbons 33 carrying different colors are secured to the single parts of the rollers 41. 50 denotes guide-rollers for the color ribbons arranged between the rollers 41.

48 is a shaft for actuating the perforators and punches provided in connection with each needle-row of the embroidery machine. To that end of each of these shafts 48 which is arranged above the driving shaft 19 is fixed a lever 51. The levers 51 are connected by means of a rod 52 having a fork-shaped lower end. The fork-shaped end of the rod 52 carries a pin 53. On the pin 53 is loose a roll 55 adapted to be moved along this pin 53 by means of a fork-like lever 54 (Fig. 1). According to the position of the lever 54, the roll 55 co-operates either with a round disk 56 or a cam disk 57 of the driving shaft 19, thus actuating either the perforators or punches of the machine.

When the hereinbefore described color transferring device is set into the inoperative position, the hand levers 21 and 31 are in the position shown in Figs. 1 and 2, the carrier A for the color-ribbons being in its lowermost position, where it is situated at a certain distance from the fabric 10 to be embroidered (Fig. 6). While the embroidery operation is proceeding, the shaft 48 remains stationary, the roll 55 resting on the round disk 56.

When it is desired to transfer color to the piece of fabric to be embroidered, the lever 31 is at first moved in the direction of arrow 58 (Fig. 1), so that the slide pieces 24¹ are caused to engage with their inclined surface 25 the bolts 26, the angle pieces 9 being thereby moved toward the fabric 10, which in turn move the ribbon carrier A from its position flush with the faces of the shuttle tracks 3 so as to clear the upper portions of said tracks that overhang the shuttle bar 7 an extent about equal to the thickness of the carrier. The ribbon-carrier A is thus moved close to the fabric 10. Hereupon, lever 21 is also moved in the direction of the arrow 58, so that the carrier A is raised between the piece of fabric 10 and the shuttle tracks 3.

By adjusting the lever 21 in a suitable manner with regard to the toothed segment 23, the carrier A for the color-ribbons can be raised such an amount, that the ribbon 33 carrying the desired color is brought on a level with the punches 6. The roll 55 is then adjusted in its turn in such a manner,

that it comes to rest on the cam-disk 57. Upon a rotation of the shaft 19, the punches 6 coupled to the latter are moved, after the piercing of the fabric 10, into the holes 36 5 and then caused to pierce the color-ribbon 33 lying on the level of the punches 6. The punches 6 take color off the ribbon and transfer it on their backward movement to the fabric to be embroidered. Should it be 10 desired to transfer another color to the fabric 10, the hand lever 21 is adjusted in such a manner, that the ribbon carrying the desired color is raised or lowered respectively, on a level with the punches 6. 15 Owing to the oscillating movement imparted to the shaft 48 while the punches 6 are moved to and fro, an oscillating movement is also imparted to the levers 45 carrying the pawls 44. The pawls 43, 44 of one 20 ratchet wheel 40 are in operative position, while the pawls of the other ratchet wheel 40 are set out of operation. In consequence of this, the oscillating movement imparted to the feed lever 45 of that feed mechanism, the 25 feed pawls of which are in operative position, imparts a feed movement to the ribbon-roller 41 mounted on the shaft 39 of said feed mechanism, so that the ribbons are gradually wound upon this roller 41; the ribbon-roller 30 41 of the other feed mechanism being acted upon by the spring 42 exerting a brake action and thus tensioning the roller-ribbons 33. When the ribbons have been wound 35 upon the roller 41, the pawls of the feed mechanism which has just been operative are then set out of operation, while the pawls of the other feed mechanism are moved into operative position, the ribbons being then rolled upon the ribbon-roller of the second 40 feed mechanism. Owing to the feed movement imparted to the color-ribbons and in consequence of the fact, that even the ribbon lying in front of the punches can be adjusted vertically with regard to the punches by 45 means of the hand lever 21, the color-ribbons are spared as much as possible, so that they may be used for a very long time. 50 50 denotes pressure-fingers provided on the ends of the shuttle bar 7 and which are 55 for causing also the free ends of the carrier A to rest on the fabric piece 10. The hereinbefore described device for transferring colors is wholly independent of the frame 2 of the embroidery machine 60 and all the means for setting the device in and out of operation are arranged near one another, so that the attendant can control all the members to be moved by him from one stand. By carrying out very simple manipulations, it is also possible to transfer in any 65 desired sequence several colors. Owing to the use of a ribbon-carrier having the shape of a flat box and consisting of flat casings, the novel device does not take up much space 65 in a transverse direction relatively to the

fabric framed in the machine, so that this device can be arranged behind the stretched fabric piece to be embroidered, *i. e.* in shuttle embroidery machines between the stretched fabric piece and the shuttle tracks. The 70 space between the framed fabric piece and the shuttle tracks is very limited in shuttle embroidery machines, so that it would be quite impossible to use in such machines an apparatus for transferring colors provided 75 with color-carriers having the shape of a cartridge sleeve or of a roller. As the roller-ribbons are guided in casings provided with holes arranged at a distance from one another corresponding to the repeat, a soiling 80 of the fabric and an intermixing of the color-ribbons is prevented. In the embodiment shown in Figs. 12-13, where the parts corresponding to similar 85 parts of the first embodiment have the same reference numbers, the two levers 21, 31 are replaced by a single lever adapted to cause as well a movement of the carrier A toward the framed fabric piece 10 as a lifting of said carrier A between the fabric piece 10 90 and the shuttle tracks. In this embodiment the movement of the carrier A in the direction of the arrow 60 (Fig. 12) is brought about by a cam 61 provided on the lever 17 adapted to be oscillated, said cam 61 co-operating with a roller 61¹ connected to the angle-piece 9. For the rest, this mechanism operates in the same manner as that shown 95 in the first embodiment.

Figs. 14 and 15 illustrate a construction 100 in which each color-ribbon is adapted to be moved independently of the other ones. To this end each ribbon is wound upon a separate roller 62¹, 62² and 62³ respectively. Each of these rollers is connected to a 105 coaxial toothed wheel 63¹, 63² and 63³ respectively. These wheels are adapted to be brought into or out of engagement with a central toothed wheel 64 arranged coaxially to the ratchet wheel 40 and formed integral 110 therewith. For this purpose the shafts 39¹ are adjustable to and from the wheel 64 in slots 70 arranged radially to the center of the wheel 64. Thumb nuts 71 hold the 115 shafts 39¹ in operative or inoperative positions for their respective gear wheels 63¹, &c. When the feed pawls adapted to co-operate with the ratchet wheel 40 are set into operative position, the central toothed wheel 64 is moved by jerks and it transmits then 120 this movement to that of the toothed wheels connected with the rollers 62¹, 62² and 62³ respectively, which just engage into said wheel 64. The rollers 62¹, 62² and 62³ respectively, connected to the toothed wheel 125 or wheels meshing with the central toothed wheel 64, are then rotated, while the other rollers remain stationary.

What I claim now as my invention is:

1. A device of the character described for 130

- transferring colors, comprising ribbons carrying colors, a carrier for the ribbons provided with holes, piercing means; means for moving the piercing means through a framed fabric, the holes in the carrier and the ribbons; and means for imparting to said carrier a rectilinear horizontal as well as a rectilinear vertical movement. 5
2. A device of the character described for transferring colors, comprising ribbons carrying colors, a carrier for the ribbons provided with holes, piercing means; means for moving the piercing means through a framed fabric, the holes in the carrier and the ribbons; means for imparting to said carrier a rectilinear horizontal movement and means independent of the last mentioned means for imparting to said carrier a rectilinear vertical movement. 10
- 20 3. In an embroidering machine having a driving shaft and shuttle tracks and a bar carrying the latter; holders distributed over the whole length of said bar and fixed thereto, a flat bar extending over the whole length of the machine and provided with a plurality of holes, said flat bar being supported by said holders, color ribbons carried and guided by said flat bar, piercing means, means actuated by the driving shaft of the 25 embroidering machine for moving the piercing means through a framed fabric, the holes provided in the flat bar and the ribbons; means for imparting to said flat bar a rectilinear horizontal movement, means independent of the last mentioned means for imparting to said flat bar a rectilinear vertical movement, and means adapted to impart to the color ribbons a feed movement upon an actuation of the piercing means by the driving shaft of the embroidering machine. 30
- 40 4. A device for transferring colors of the character described, comprising ribbons carrying colors, a flat carrier consisting of a plurality of superposed casings, the carrier acting as a guide for the ribbons and being provided with holes, piercing means, means for moving the piercing means through a framed fabric, the holes provided in the carrier and the ribbons, and means for adjusting the carrier. 45
- 50 5. A device for transferring colors of the character described, comprising ribbons carrying colors, a flat carrier acting as a guide for the ribbons and provided with holes arranged at a distance from one another corresponding to the repeat, piercing means, means for moving the piercing means through a framed fabric, the holes provided in the carrier and the ribbons, and hand 55 levers for adjusting the flat carrier as well in a vertical as horizontal direction. 60
- 65 6. A device for transferring colors of the character described, comprising ribbons carrying colors, a flat carrier for the ribbons provided with holes, bars supporting the carrier, angle pieces, the bars being movably mounted on the angle pieces, means for moving the angle pieces in a horizontal direction, stationary supports carrying the angle pieces, means for moving the bars supporting the flat carrier in a vertical direction, piercing means and means for moving the piercing means through a framed fabric, the holes provided in the carrier and the ribbons. 70
- 75 7. A device for transferring colors of the character described, comprising ribbons carrying colors, a flat carrier for the ribbons provided with holes, bars supporting the carrier, angle pieces, stationary supports carrying the angle pieces, shafts rotatably mounted in the stationary supports, a lever fixed to each of said shafts and operatively connected to one of said bars supporting the carrier, means connecting said levers, a hand lever, means operatively connecting the hand lever to said means connecting the levers fixed to the rotatable shafts, slidable members provided with an inclined surface and mounted on the stationary supports, a pin 80 on each angle piece, means connecting said slidable members, springs acting upon the slidable members and having the tendency to press the slidable members against the pins provided on said angle pieces, a second 85 hand lever operatively connected to the means connecting the slidable members and adapted to cause the inclined surface of the slidable members to engage the pins on the angle pieces, piercing means and means for 90 moving the piercing means through a framed fabric, the holes provided in the carrier and the ribbons. 95
- 100 8. A device for transferring colors of the character described, comprising ribbons carrying colors, a carrier for the ribbons provided with holes, piercing means, means for moving the piercing means through a framed fabric, the holes provided in the carrier and the ribbons, movable rollers, each 105 ribbon being connected at each end to one of said rollers, means adapted to impart to the rollers a feed movement and means effecting an operative connection between the means moving the piercing means and the 110 feed means for the rollers. 115
- 120 9. A device for transferring colors of the character described, comprising ribbons carrying colors, a carrier for the ribbons provided with holes, a rotatable shaft, means for driving the rotatable shaft, piercing means receiving a to and fro movement from said shaft, so that said piercing means are moved through a framed fabric, the holes provided in the carrier and the ribbons, movable rollers, each ribbon being connected at each end to one of said rollers, feed mechanisms adapted to impart a feed movement to said rollers, operative connections between said rotatable shaft and the 125 130

feed mechanisms adapted to actuate said feed mechanisms upon an actuation of the shaft and means for adjusting the carrier for the ribbons as well in a vertical as horizontal direction.

10. In an embroidering machine having a shuttle track bar; shuttle tracks overhanging said bar, means for carrying color arranged beneath the overhanging portion of the tracks, and mechanisms to first move said means from beneath said overhanging portion and then up between the fabric and the shuttle tracks.

11. In an embroidering machine the combination with shuttle tracks, a bar supporting the same and means for stretching a ground fabric adjacent said tracks; of color carrying means and mechanism to move said means parallel to fabric and shuttle tracks and between the same.

12. In an embroidering machine, the combination with shuttle tracks and a bar carrying the same; of means for carrying a plurality of color carrying devices in superposed relation, and mechanism to move said means parallel to said tracks to move any one of said devices into operative position.

13. In an embroidering machine, the combination with a supporting bar, shuttle tracks overhanging said supporting bar; of means carrying a plurality of color ribbons in superposed relation and arranged beneath the overhanging portion of said tracks when in inoperative position, mechanism to move said means from under the overhanging portion and separate mechanism to move said means parallel to said tracks to operatively position any ribbon in front of said tracks.

14. In an embroidering machine, the combination with shuttle tracks and a bar supporting them; of a color ribbon carrier having a plurality of color ribbons therein, mechanism to move said carrier in parallel relation to the tracks and into any one of a number of operative positions, feed mechanism for the ribbons including a single actuator and manually adjustable means to cause said actuator to feed the particular color ribbon for the time being in operative position.

In testimony that I claim the foregoing as my invention, I have signed my name.

CHARLES WILLIAM WETTER.
